UNITED STATES PATENT OFFICE.

JAMES C. GAFFNEY, OF NEW YORK, N. Y.

DESIGN FOR A DOLL.

Application filed April 13, 1922. Serial No. 1,732. Term of patent 3½ years.

To all whom it may concern:

Be it known that I, JAMES C. GAFFNEY, a citizen of the United States, residing in the city, county, and State of New York, have invented a new, original, and ornamental Design for a Doll, of which the following is a specification, reference being had to the accompanying drawing, forming a part thereof, wherein—

What I claim is the ornamental design for a doll, as shown.

JAMES C. GAFFNEY.
